CONTAINER

Raymond M. Schlabach, Canton, Ohio

Application February 19, 1941, Serial No. 379,613

7 Claims. (Cl. 221—64)

My invention relates to containers, more particularly adapted for powders, which have openings and attached closures which are operative to provide a substantially but not entirely airtight seal for the openings, and which are easily operated to cover and uncover the openings.

Usual containers for powders, or granular or comminuted material, which should be kept from continuous exposure to the atmosphere, include cans made of sheet metal such as tin plate, terne plate, or black iron, each having a top wall with an opening which is usually circular and in which is wedge fitted a plug closure usually in the form of a sheet metal flanged cup.

For removing the usual plug closure, a prying action is utilized and it is necessary to apply considerable wedging pressure in replacing the plug closure in the container opening to effect a substantial seal of the opening.

Because of the necessity of wedging the usual plug closure into the opening of a usual can container, there is a tendency on the part of users of the same to loosely insert the plug closure in the opening without effecting a satisfactory seal.

The objects of the present improvements include the provision of an improved container particularly adapted for powders, or granular or comminuted material, which it is desirable to protect from the atmosphere, and the container having an opening with a closure operatively attached and which is adapted for easily covering and uncovering the opening and for effecting a substantially but not necessarily entirely airtight seal for the opening when in the covering position.

Further objects of the present improvements include the provision of an improved container having an opening with an attached closure operative for covering and uncovering the opening, all the parts of the improved container being adapted to be made of sheet metal by usual machinery in a usual can manufacturing plant.

The foregoing and other objects are attained by the containers, parts, combinations, and sub-combinations comprising the present invention, the nature of which is set forth in the following general statement, and preferred embodiments of which are set forth in the following description, and which are particularly and distinctly pointed out and set forth in the appended claims forming part hereof.

The nature of the improved container of the present invention may be stated in general terms as including a preferably cylindric tubular body,

preferably of usual seamed can construction, and which has a usual circular cup bottom applied with a single bead or seam after the container has been filled from the bottom with powder or other material.

At the other top end of the tubular body, a can head is attached, and immediately above the can head a rotary top disk is located, and immediately above the rotary top disk an annular bearing ring is beaded or seamed with the can head to the upper end of the tubular can body.

The rotary top disk has an upwardly protruding handle, preferably an outwardly protruding circular bead or ridge adjacent the inner annular edge of the ring, an opening at one side of the handle, and preferably diametrically opposite the opening, a depression forming a downwardly protruding plug corresponding in shape to the opening.

The can head has at one side of its center an opening corresponding in area and fitting with the opening in the rotary top disk and the sealing plug thereof, and the can head also has an upwardly opening curved channel depression whose ends are spaced from the opening in the head, the curvature of the channel depression being circular and being arcuately aligned with the sealing plug in the rotary top disk, whereby rotation of the top disk serves to spring the plug in the top disk to and from the opening in the can head and into and out of the curved channel therein.

By way of example, a preferred embodiment of the improved container hereof is illustrated in the accompanying drawing forming part hereof, in which

Figure 1 is a top plan view of a container including the present improvements with a portion of the rotary top disk broken away to show the can head immediately beneath;

Fig. 2, an enlarged fragmentary vertical transverse sectional view as on line 2—2, Fig. 1; and

Fig. 3, a top plan view of the can head prior to assembly.

Similar numerals refer to similar parts throughout the several views.

The improved container indicated generally by 10 is preferably of sheet metal construction, the sheet metal being tin plate, terne plate, black iron, or other similar material used in can manufacturing and the like.

The improved container 10 includes a cylindric tubular body 11 which may have a usual longitudinal seam 11a. At one end of the cylindric tubular body 11 there is provided a usual bottom wall 11b of cup construction and secured by a

single seam in a usual manner to the lower extremity of the cylindric tubular body 11.

In the top portions of the container 10, a can head wall 12 extends across the other end of the cylindric tubular body 11. Immediately above the head wall 12 a rotary disk indicated generally by 13 rotatably fits within the end of the cylindric body 11. Immediately above the rotary disk 13 there is located an annular sealing and bearing ring 14, inner preferably circular peripheral portions of which retain the disk 13 against the head wall 12.

The upper extremity of the cylindric tubular body 11 and the outer peripheral portions of the head wall 12 and the ring 14 are spun to make an annular bead seam 15 in a usual manner.

The rotary top disk 13 is formed with an upwardly protruding circular bead ridge 16 adjacent the inner annular edge 17 of the ring 14, and an opening 18 is formed in the rotary top disk 13 at one side of its center, and preferably diametrically opposite the opening 18 there is formed in the rotary disk 13 a depression protruding downwardly as a plug 19.

The can head wall 12 has at one side of its center an opening 20 corresponding in area and registerable with the disk opening 18 and adapted to receive the sealing plug 19 of the rotary disk 13.

The can head wall 12 also formed therein an upwardly opening curved channel depression 21 whose ends 22 and 23 are spaced some distance away from the opening 20, and the curvature of the channel depression 21 is circular and is arcuately alined with the opening 20 of the head wall 12 and also with the sealing plug 19 of the rotary disk 13.

In the drawing, the rotary disk 13 is shown in sealed position, with the sealing plug 19 extending into the opening 20 of the head wall 12.

For facilitating rotation of the disk 13, the disk 13 may be formed with a central radially extending upwardly protruding handle 24.

When it is desired to gain access to the powder or other material in the interior of the improved can 10, the tubular body 11 is held by one hand, and the handle 24 of the rotary disk 13 is turned with the other hand, springing the sealing plug 19 out of the head wall opening 20, and then riding it into the circularly curved channel depression 21, after which further turning effects registration of the opening 18 of the rotary disk 13 with the opening 20 of the head wall 12.

For again closing the head wall opening 20 reverse rotation of the disk 13 is effected, springing the plug 19 out of the channel 21 and into the head wall opening 20.

By the foregoing construction, a sufficiently air-tight seal is attained for powders or similar material in common use which have heretofore had plug type friction tops which have been very difficult to open and which are usually not closed properly.

Moreover, the arrangement of the parts, and particularly the provision of the circular head ridge 16 adjacent the inner annular edge 17 of the ring 14, prevents catching of the finger nails beneath the ring 14, and similar undesirable accidents.

The bearing ring 14 as shown and preferably has an inner outwardly concave frusto-conical flange 25 sloping from the seam 15 towards the rotary disk 13 and having the inner annular edge 17 abutting the rotary disk 13. By thus providing the inner frusto-conical flange 25 on the

bearing ring 14, the closure of the head wall opening 20 by the plug 19 of the disk 13 is facilitated by a yielding springing action, and the springing of the sealing plug 19 out of the head wall opening 20 when the disk 13 is rotated from the sealing position is also facilitated.

For further facilitating the springing of the plug 19 into and out of the head wall opening 20 and out of and into the channel 21, the sides of the plug 19 are preferably sloping as best shown in Fig. 2, and the sides of the channel 21 are preferably provided with corresponding slopes.

From a broad standpoint, the head wall 12, the rotary disk 13, and the bearing ring 14, assembled together as above set forth with the disk rotatable between the head wall 12 and the bearing ring 14, and with the outer peripheral portions of the head wall 12 and the bearing ring 14 secured together, constitute an improved openable and closable closure construction for any opening, which as shown is the upper end of the tubular can body 11.

The embodiments of the present improvements illustrated and described herein are by way of example, and the scope of the present invention is not limited to the same or to the particular details thereof, but is commensurate with any and all novel subject matter contained herein which may at any time properly under the United States patent laws be set forth in the claims hereof or originating herein, and the elements of any such claims are intended to include their reasonable functional or structural equivalents.

I claim:

1. In closure construction for a container and the like, a wall having formed therein an opening and a curved channel formed separately in the wall from the opening and having ends spaced from the opening, the curved channel being circular and being arcuately alined with the opening, a rotary disk at one side of the wall, the rotary disk having formed therein an opening registerable with the wall opening, and the disk having on its side adjacent the wall a plug spaced from the disk opening and rotatable with the disk into and out of the wall opening and from and in the curved channel, and spring bearing ring means extending from the wall over outer peripheral portions of the disk and retaining the disk against the wall.

2. In closure construction for a container and the like, a wall having formed therein an opening and a curved channel formed separately in the wall from the opening and having ends spaced from the opening, the curved channel being circular and being arcuately alined with the opening, a rotary disk at one side of the wall, the rotary disk having formed therein an opening registerable with the wall opening, and the disk having on its side adjacent the wall a plug spaced from the disk opening and rotatable with the disk into and out of the wall opening and from and in the curved channel and the disk having on the other side a circular ridge, and a bearing ring including outer peripheral portions secured to the wall and inner circular peripheral portions engirdling the circular ridge on the disk and retaining the disk against the wall.

3. In closure construction for a container and the like, a wall having formed therein an opening and a circularly curved channel formed separately in the wall from the opening and having an end spaced from the opening, the channel being arcuately alined with the opening, a rotary disk at one side of the wall, the rotary disk hav-

ing formed therein an opening registerable with the wall opening, and the disk having on its side adjacent the wall a plug spaced from the disk opening and rotatable with the disk into and out of the wall opening and from and in the channel, and means retaining the disk against the wall.

4. In closure construction for a container and the like, a wall having formed therein an opening and a channel formed separately in the wall from the opening and having an end spaced from the opening, a disk at one side of the wall, the disk having formed therein an opening registerable with the wall opening, and the disk having on its side adjacent the wall a plug spaced from the disk opening, and means mounting the disk for movement of the plug into and out of the wall opening and from and in the channel, the openings being registerable with each other when the plug is in the channel.

5. In closure construction for a container and the like, a wall having formed therein an opening and a channel formed separately in the wall from the opening and having an end spaced from the opening, a disk at one side of the wall, the disk having formed therein an opening registerable with the wall opening and the disk having on its side adjacent the wall a plug spaced from the disk opening, and flange means secured to the wall and having portions sloping towards the disk and retaining the disk against the wall and permitting movement of the disk for moving the plug into and out of the wall opening and from and in the channel, the openings being registerable with each other when the plug is in the channel.

6. In closure construction for a container and the like, a wall having formed therein an opening

and a circularly curved channel formed separately in the wall from the opening and having an end spaced from the opening, the channel being arcuately alined with the opening, a rotary disk at one side of the wall, the disk having formed therein an opening registerable with the wall opening, and the disk having on its side adjacent the wall a plug spaced from the disk opening, and bearing ring means at the other side 10 of the disk, the bearing ring means having outer peripheral portions secured to the wall and having inner frusto-conical flange portions sloping towards the disk and retaining the disk against the wall, the associated wall and bearing 15 ring means permitting rotary movement of the disk for moving the plug into and out of the wall opening and from and in the channel, the openings being registerable with each other when the plug is in the channel.

7. In closure construction for a container and the like, a wall having formed therein an opening and a channel formed separately in the wall from the opening and having an end spaced from the opening, a disk at one side of the wall, the disk 20 having formed therein an opening registerable with the wall opening, and the disk having on its side adjacent the wall a plug spaced from the disk opening, and means mounting the disk for movement of the plug into and out of the wall opening and from and in the channel, the openings being registerable with each other when the plug is in the channel, the plug having sloping, 25 side walls for facilitating springing of the plug into and out of the opening and from and in the channel.

RAYMOND M. SCHLABACH.
